CLAIM

(22) Filed: **Aug. 21, 2007**

The ornamental design for a cover for motorcycle lower inner fairing, as shown and described.

(51) **LOC (8) Cl.** 12-11

DESCRIPTION

(52) **U.S. Cl.** D12/126

FIG. 1 is an environmental perspective view of a cover for motorcycle lower inner fairing showing my new design;

(58) **Field of Classification Search** D12/110,

FIG. 2 is a front elevational view thereof;

D12/112, 114, 126, 117, 118, 190, 191, 182,

FIG. 3 is a rear elevational view thereof;

D12/186; 280/288.4, 304.3, 152.1-152.3,

FIG. 4 is a right side elevational view thereof;

280/770, 848, 852, 304.4, 276, 279; 180/219,

FIG. 5 is a left side elevational view thereof;

180/220, 225; 296/78.1, 180.1, 192, 193.01,

FIG. 6 is a top view thereof; and,

296/193.05, 193.09, 77.1

FIG. 7 is a bottom view thereof.

See application file for complete search history.

The broken line showing of the portion of a motorcycle in FIG. 1 is for illustrative purposes only and forms no part of the claimed design.
